UNITED STATES PATENT OFFICE.

GEORGE E. FARLEY, OF LOS ANGELES, CALIFORNIA, ASSIGNOR TO SERVICE EQUIPMENT COMPANY, OF HUNTINGTON PARK, CALIFORNIA, A CORPORATION OF CALIFORNIA.

SERVICE TOWER.

Application filed February 15, 1923. Serial No. 619,171.

To all whom it may concern:

Be it known that I, GEORGE E. FARLEY, a citizen of the United States, residing at 1727 West 24th Street, Los Angeles, in the county of Los Angeles and State of California, have invented new and useful Improvements in Service Towers, of which the following is a specification.

My invention relates to service towers of the character embodied in my co-pending application Serial No. 528,724 filed January 12, 1922, and a purpose of my present invention is the provision of a service tower having a plurality of air hose supporting levers which are mounted to rotate and rock independently of each other and without the possibility of interference so that either or both hose can be manipulated to supply air to the tires of a single motor vehicle or to two irrespective of its or their positions within the range of the hose.

It is also a purpose of my invention to provide a service tower including a standard having simple and efficient brackets for securing pipes comprising the standard in triangular formation the construction of the brackets being such that an additional pipe within the triangular arrangement can be securely held in proper position.

Among the other purposes of my invention is the provision of a service tower having novel means for rotatably supporting the levers; counterbalancing the levers so that they normally occupy upstanding positions; providing an adjustable and yieldable bumper to eliminate jars and shocks to the levers and their supporting elements; and providing adjustable and removable means for normally urging the levers to a predetermined position circumferentially with respect to a vertical axis.

Although I have herein shown and described only two forms of service towers embodying my invention, it is to be understood that various changes and modifications may be made herein without departing from the spirit of the invention and the spirit and scope of the appended claims.

In the accompanying drawings,

Figure 1 is a view showing in front elevation one form of a service tower embodying my invention.

Fig. 2 is a view showing in side or edge

elevation the service tower shown in Fig. 1.

Fig. 3 is a transverse sectional view taken on the line 3—3 of Fig. 2.

Fig. 4 is a transverse sectional view taken on the line 4—4 of Fig. 2.

Fig. 5 is an enlarged fragmentary view of a portion of the standard comprised in the tower shown in Fig. 2, and one of the brackets for securing the pipes in proper position.

Fig. 6 is a view showing in front elevation and partly in section a portion of one of the hose supporting levers and its mounting.

Fig. 7 is a vertical sectional view taken on the line 7—7 of Fig. 6.

Figures 8, 9, and 10, are sectional views taken on the lines 8—8, 9—9, and 10—10, respectively, of Fig. 7.

Fig. 11 is a fragmentary sectional view of the upper end of one of the hose supporting levers showing one manner in which the hose is movably associated with the lever.

Fig. 12 is a vertical sectional view taken on the line 12—12 of Fig. 11.

Figures 13 and 14 are views showing in front and side elevation, respectively, another form of service tower embodying my invention.

Figures 15 and 16 are transversely sectional views taken on the lines 15—15 and 16—16, respectively, of Fig. 14.

Similar reference characters refer to similar parts in each of the several views.

Referring specifically to the drawings and particularly to Figures 1 and 2, my invention in its present embodiment comprises a standard designated generally at S and including a plurality of pipes having their lower ends embedded in a base B formed of concrete or other suitable material. The pipes comprising the standard S include an air pipe 15, an electrical conduit 16, a water pipe 17 and a supporting pipe 18 through which no fluid is adapted to flow. Air under pressure is adapted to be supplied to the lower end of air pipe 15 by means of a pipe 15^a, and air from the pipe 15 is adapted to be supplied to flexible air hose 19 and 20 by means of a common branch pipe 21 which is clearly shown in Fig. 1 as provided with a nipple 22 at a point intermediate its ends 105 which is connected to the upper end of pipe

15 by means of a union 23. An extension 24 is formed on the pipe 21 adjacent to the nipple 22 and a union 25 connects this extension with the upper end of the pipe 18. 5 It is to be understood that the extension is solid and that the pipe 18 is connected thereto merely for the purpose of providing additional supporting means for the branch pipe 21.

10 The pipes 15, 17, and 18 are arranged in triangular formation as clearly shown in Fig. 4, and the electrical conduit 16 is disposed centrally of the triangle formed by the pipes 15, 17, and 18. These latter pipes are 15 rigidly secured in triangular formation by means of brackets K arranged at suitable intervals along the length of the pipes as shown in Fig. 1. As shown in Fig. 4, each bracket K includes three clamping plates 26 20 each having oppositely curved extremities 27 and a curved medial portion 28 connected to the curved extremities by tapered portions 29. Bolts 30 or other suitable fastening members are extended through the tapered 25 portions 29 of any two adjacent plates 26 for securing the latter in clamping relation with respect to the pipes and conduit. As 30 illustrated in Fig. 4, the curved extremities 27 of adjacent plates embrace the pipes 15, 35 17, and 18, while the medial portions 28 of all of the plates engage the conduit 16. With this arrangement it will be seen that the plates of the brackets serve to rigidly secure the pipes in triangular formation, and the conduit centrally within the standard.

Referring again to Fig. 1, it will be seen that the distributing pipe 21 is provided at its opposite ends with valved extensions 31 to which the hose 19 and 20 are connected. 40 These hose 19 and 20 are adapted to be supported by means of levers L and L', respectively, mounted to rotate in a horizontal plane and to oscillate in a vertical plane. As the construction of the levers and the mountings therefore are the same, a description of one will suffice for both. As shown in Fig. 2 each lever L or L' comprises a pair of spaced pipes 32 flattened at their lower ends for rigid connection to a pair of arms 45 33 which latter in turn are mounted for rocking movement upon a bolt or shaft 34 which as clearly shown in Fig. 6 is embraced by a bearing sleeve 35 threadedly engaging the upper end of a tubular member 37 rotatably fitted on an upright 38 formed of cold rolled steel. The upright 38 is welded or otherwise secured at its lower end by a branch pipe 21 as clearly shown in Fig. 7 while the upper end is provided with a pocket 50 upon which is mounted a ball bearing 39 arranged to have rolling contact with the bearing sleeve 35.

By this arrangement, it will be seen that the tubular member 37 is antifrictionally 60 supported for rotational movement upon

the upright 38 so as to allow of the arms 33 and consequently the pipes 32 to rotate about the upright as a center. The ball bearing 39 also serves to rotatably support the bearing sleeve 35 and to thus permit of the 70 rocking of the arms 33 upon the upright.

The hose 19 or 20 is connected to the lever L or L' between the pipes 32 and, in the present instance by means of a collar 40 secured between the pipes 32 as shown in Fig. 75 1, and a movable bracket 41 rotatably mounted at the upper ends of the pipes 32 in the manner clearly shown in Figs. 11 and 12. As here shown, the bracket 41 includes semi-circular members 42 which loosely receive 80 a spring sleeve 43 surrounding the hose 19 or 20. The members 42 are provided with flanges 44 through which bolts 45 extend for securing the members in circular formation. The members 42 are provided with stub 85 shafts 46 which are journaled in extensions 47 and secured therein by cotter pins 48. The extensions 47 are fitted in and riveted or otherwise secured to the upper ends of the pipes 32 so that the bracket 41 is mounted 90 for rotational movement between the pipes. This arrangement obviously provides means for movably supporting the hose 19 so as to allow unrestricted movement thereof during the manipulation of the hose and 95 lever. By supporting the hose between the pipes 32 through the medium of the collar 40 and the bracket 41 it will be manifest that the hose is held out of contact with the pipes 32 so that excessive wear as a result of 100 engaging the pipes will be eliminated.

The lower ends of the arms 33 carry weights 49 adjustably supported upon the arms in the manner clearly shown in Fig. 6. 105 These weights serve to normally urge the lever to an upstanding position as clearly shown in Fig. 1 so that irrespective of the position of the lever when the hose 19 or 20 is released, such lever will return to the upstanding position. To provide a yieldable 110 abutment or bumper for the lever L or L' as it returns to the normal position I provide the device illustrated in Figs. 7 and 9. This device in the present instance comprises a bar 50 formed with openings to 115 slidably receive bolts or rods 51 secured at one end to the arms 33 and provided at the other end with heads 52. Coiled expansible springs 53 are interposed between the heads 52 and the arms 33 so as to normally urge the bar 50 in the direction of the arms 33. The bar 50 carries a strip 54 of rubber or other suitable material which is adapted to contact with the tubular member 37 when the lever L or L' is in normal position. The heads 52 are adjustable to vary the tension of the springs 53 so that the yielding action 120 of the device can be regulated accordingly.

Referring now to Figs. 1 and 7, means is 125 shown for normally urging the member 37 130

to a predetermined position circumferentially with respect to the upright 38 so that the lever L or L' when at rest will occupy a definite position with respect to the upright 38 and the other lever L or L'. This means in the present instance comprises a rod 55 formed of resilient metal and fitted at its lower end within a block 56, the latter being secured to the distributing pipe 21 adjacent to the upright 38 by means of bolts 57. As shown in Fig. 7, the block 56 is provided on its under side with a groove 56a which receives the lower and bent end 55a so that when the block is in clamped position on the pipe, the rod will be securely held within the block and against any turning movement. A bracket 58 is adjustably mounted upon the tubular member 37 so as to occupy any desired vertical position. This bracket 58 is adapted to clampingly engage the rod 55 so that when the member 37 is rotated on the upright 38, the rod 55 will be flexed circumferentially thus placing the rod under tension. The positioning of the rod 55 is such that the member 37 and consequently the lever L or L' is urged to the position shown in Fig. 1, so that any movement of the lever in one direction or the other from this urged position will place the rod 55 under such tension that when the lever is released the rod will operate to return the lever to normal position. Should the lower end of the rod 55 break after prolonged use, a renewal may be effected by merely lowering the rod within the bracket 58 and the block 56 and then rebending the lower end of the rod, as will be understood.

The rotational movement of the member 37 upon the upright 38 is limited in both directions by means of a projection 59 formed on the lower end of the member 37 and arranged to engage the block 56 on either side of the latter depending upon the direction in which the member 37 is rotated. It will be clear that by this arrangement, the rotational movement of the lever L or L' about the upright 38 is necessarily limited, and the arrangement of the stop 59 is such as to prevent possible interference of the lever L with the lever L'.

The hose 19 and 20 when not in use are adapted to be placed within the hooked ends 60 of a bar 61 suitably supported upon the standard S in the manner shown in Fig. 1. The water pipe 17, as shown in Fig. 2 is provided with a spigot 62 to which a hose 63 is connected. This hose when not in use is supported upon a bracket 64.

The electric conduit 16 is provided at its upper end as shown in Fig. 2 with a substantially L-shaped extension 65, with its free end disposed at one side of the standard and provided with a lamp 66 and a shade 67. By supporting the lamp 66 in this manner it will be clear that when the lamp is

illuminated sufficient light will be provided to allow the use of the service tower at night.

As shown in Fig. 3, the branch pipe 21 has secured thereto by means of brackets 68, guard members 69 which serve to prevent the entanglement of the hose 19 and 20 with any part of the service tower. These guards in the present instance are formed of relatively heavy wire bent substantially in the form of an annulus 69 and having their ends secured within the brackets.

Referring now to Figs. 13 and 14, I have here shown another form of service tower embodying my invention which is similar in construction to the first service tower described in that the standard S includes an air pipe 70, a water pipe 71 and a supporting pipe 72 secured in triangular formation by means of brackets K. A conduit 72a is arranged centrally of the triangle and secured to the other pipes by the brackets. An upper end of the conduit 72a is connected to a T 73, and extending upwardly from the T is a solid bar 74 of cold rolled steel upon which is rotatably mounted member 75. The members 74 and 75 are the equivalent of the members 37 and 38 and an arm L² is associated with the member 75 to allow of rocking movement thereof and to rotate with the member upon the solid member 74. Rotational movement of the member 75 is limited in either direction by means of stops 76 which, as clearly shown in Fig. 15 are adapted to engage a stop finger 77 pivoted at 78 and normally urged to a definite position by means of springs 79. The finger 77 and the springs 79 are mounted on a yoke 80 secured to the upper ends of certain of the pipes as shown in Fig. 14. The branch conduit 81 extends from the T 73 and connects with a junction box 82 from which latter extend light supporting conduits 83.

The valved extension 84 is connected to the upper end of the air pipe 70 and to a flexible air hose 85 secured to the lever L² in the same manner as that described in connection with the hose 19 and 20. A faucet 87 is connected to the water pipe 72 and to a hose 88 normally supported upon a bracket 89.

What I claim is:

1. A service tower having a transversely extending air supply and distributor pipe, an air hose connected to each end of the distributor pipe, lever arms independently turnable about vertical axes on the ends of the distributor pipe, and being pivotally mounted to swing from substantially upright positions downwardly, said hose being mounted in the swinging ends of the lever arms, which latter are adapted to sweep about their vertical axes independently of each other.

2. A service tower comprising an upstanding air pipe, a common distributing head

- pipe communicating with the first pipe and mounted transversely on the upper part of the same, hose connected to the ends of the common pipe, and levers supported on the 5 ends of the common pipe for movement vertically and horizontally, and normally urged to upright positions, said hose being supported on the levers to normally occupy retracted positions.
- 10 3. A service tower comprising an upstanding air pipe, a head pipe communicating with the first pipe and mounted transversely on the top of the same, hose connected to the ends of the head pipe, the latter forming a common supply, levers supported on the head pipe for pivotal, independent movement vertically and horizontally, and normally urged to upright positions, said hose being supported on the levers to normally occupy retracted positions, and means including turning tubes for carrying and limiting the horizontal movement of the levers to prevent interference of one lever with the other.
- 15 4. A service tower comprising an upstanding air pipe, a common branch air pipe communicating with the first pipe transversely of the same, hose connected to the branch pipe, levers supported on the branch pipe for independent, swinging movement vertically and horizontally, and normally urged to upright positions, said hose being supported on the levers to normally occupy retracted positions, turnable 30 means on ends of the common pipe for limiting the horizontal movement of the levers to prevent interference of one lever with the other, and means on the ends of the common pipe for preventing the hose from 35 becoming entangled in the lever and pipes.
- 40 5. A service tower comprising a standard including a fixed air pipe, a lever mounted on the pipe for rocking movement about a horizontal axis and rotational movement about a vertical axis, a spring rod, fixed at one end to the pipe for urging the lever to predetermined position with respect to the vertical axis, and a hose having a loop 45 hung on the lever and connected to one end of the fixed air pipe.
- 50 6. A service tower comprising a standard including a fixed air pipe, a lever mounted on one end of the pipe for rocking movement about a horizontal axis and rotational movement about a vertical axis, a spring 55 rod for urging the lever to predetermined position with respect to the vertical axis,
- and means for urging the lever to an upright position.
7. A service tower including a branch air 60 pipe, a vertical tube rotatable on the outer end of the pipe and normally urged to a definite position, a cross shaft rotatable in the tube and about an axis at right angles thereto, a lever fixed to the shaft, and hose 65 carried by the lever.
8. A service tower comprising a support, a branch pipe on said support, a vertical member rotatable on the outer end of said pipe and normally urged to a definite position, a fixed post on which said member is mounted, a shaft rotatable in the member and about an axis at right angles to the post, and an antifriction bearing interposed 70 between the post and the shaft.
- 75 9. In combination, a lever normally urged to a vertical position and comprising spaced side parts, and a hose loop carried by and between the said parts and movable on the lever end.
- 80 10. In combination, a horizontal air pipe, a lever mounted on one end of the pipe to rotate about vertical and horizontal axes, means for yieldably urging the lever to definite positions vertically and horizontally, a hose carried by the lever and a guard ring on the pipe for preventing the 85 hose from becoming entangled in the lever and its mounting.
- 90 11. In combination, a fixed air pipe, a lever mounted on one end of the pipe to rotate about vertical and horizontal axes, and means for yieldably urging the lever to a definite position with respect to the vertical axis comprising a rod spring attached 95 to said pipe and associated with the lever to be twisted to oppose the movement of the lever in a horizontal plane.
- 100 12. An air service tower comprising an upright standard, a transversely extending supporting member rigidly mounted upon said standard, lever arms independently turnable about vertical axes upon the ends of said supporting member and being pivotally mounted to swing from substantially 105 upright positions downwardly, means for urging said lever arms into normal predetermined positions, hose carried by the swinging ends of said lever arms, and means for delivering compressed air to said hose.
- 110 In testimony whereof I have signed my name to this specification.

GEORGE E. FARLEY.
